CLAIM

The ornamental design for a data processing device, as shown and described.

DESCRIPTION

FIG. 1 is a front elevation view of a data processing device, showing our new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front, top, right side perspective view; and,

FIG. 8 is a front, bottom, left side perspective thereof.

The broken lines in the drawings depict portions of the data processing device that form no part of the claimed design.

1 Claim, 8 Drawing Sheets
